LIGHTING FIXTURE

Howard A. Daum, Gettysburg, Pa., assignor to Hadco Products, Inc., Littlestown, Pa., a corporation of Pennsylvania

Filed July 15, 1969, Ser. No. 18,208

Term of patent 14 years

Int. Cl. D26—03, 02
U.S. Cl. D48—31

Fig. 1

Fig. 3

FIG. 1 is an elevational view of the lighting fixture showing the preferred embodiment of my new design;

FIG. 2 is a perspective view of the lighting fixture shown in FIG. 1; and

FIG. 3 is a top plan view of the lighting fixture shown in FIGS. 1 and 2.

I claim:

The ornamental design for a lighting fixture, substantially as shown and described.
